UNITED STATES PATENT OFFICE.

FLORENCE LOUISE PENGLASE, OF NEW YORK, N. Y.

DESIGN FOR A BAG.

Application filed November 14, 1924. Serial No. 11,371. Term of patent 3½ years.

To all whom it may concern:

Be it known that I, FLORENCE LOUISE PENGLASE, a citizen of the United States of America, residing in the city, county, and State of New York, have invented a new and original Design for Bags, of which the following is a specification, reference being had to the accompanying drawing.

I claim:

The ornamental design for a bag as shown.

FLORENCE LOUISE PENGLASE.
